APPARATUS FOR OPERATING ON COILED SHEET MATERIAL

Leonard A. Yoder, Lakewood, Ohio, assignor to
The Yoder Company, Cleveland, Ohio, a corporation of Ohio

Application December 15, 1937, Serial No. 179,922

1 Claim. (Cl. 242--55)

This invention relates to apparatus for operating on sheet material which is handled in coil form; that is, the material is supplied to or mounted on the apparatus in wound up or coiled form and then conducted to and through an operating mechanism and re-wound or re-coiled, whereupon it is removed from the apparatus.

The apparatus herein disclosed has been applied by me to sheet metal, but it is obvious that the apparatus may be used for other kinds of materials.

One object of the invention is to provide an improved apparatus of this type wherein provision is made for loading or mounting on the apparatus a coil of material which is to be operated upon and unloading or removing therefrom another coil of material which has been finished, during the operation of the apparatus on one coil, whereby both time and labor are saved.

Another object of the invention is to provide an apparatus of this type which is relatively simple and readily operated.

Other objects of the invention will be apparent to those skilled in the art to which my invention relates from the following description taken in connection with the accompanying drawings, wherein

Fig. 1 is a plan view of an apparatus embodying my invention.

Fig. 2 is a section on the line 2--2 of Fig. 1. Figs. 3, 4 and 5 are sections on the lines 3--3, 4--4 and 5--5, respectively, of Fig. 2.

Fig. 6 is a section on the line 6--6 of Fig. 1.

Fig. 7 is a section on the line 7--7 of Fig. 6.

Fig. 8 is a section on the line 8--8 of Fig. 7.

Fig. 9 is a fragmentary section on the line 9--9 of Fig. 6.

Fig. 10 is a section on the line 10--10 of Fig. 9.

Fig. 11 is a fragmentary plan view showing a modified form of construction.

In the drawings, 1 indicates as an entirety a mechanism for loading one coil of material A and simultaneously uncoiling a separate coil of material. 2 indicates as an entirety a mechanism for operating on the material as it uncoils from the mechanism 1. 3 indicates a mechanism for re-coiling the material as it feeds from the operating mechanism 2 and supporting the previously re-coiled material and permitting the unloading thereof while the coil of material being operated upon is re-coiled.

Of the mechanism 1, 4 indicates a suitable base supporting an upright shaft 5 on which rotates a head 6, the head resting on the upper end of the base and held thereon by a cap plate 7 suit-

ably bolted to the upper end of the shaft 5. By preference, the base 4 and shaft 5 are integral, as will be understood from Fig. 5. The head 6 is provided with a plurality of hollow, radially extending bosses 8, into each of which is fitted the inner end of a shaft 9 carrying on its outer end a collapsible drum, indicated as an entirety at 10. I have, in Figs. 1 and 2, shown two shafts 9, each carrying a drum, in diametrical relation, but it will be obvious that provision may be made for a larger number of shafts each carrying a drum, if desired. For sake of clearness in the description the drum in operative position is designated 10 and the other drum is designated 10'. Provision is made for locking the head 6 in predetermined operative positions, wherein each of the drums 10, 10', may be aligned with the mechanism 2. By preference I provide a clamping means 11 and a registering means 12, to secure the head in each operative position. The clamping means 20 consists in splitting the wall of the head 6, as shown at 13, and providing on the wall at opposite sides of the split 13 devices capable of contracting the wall into engagement with the shaft 5. The clamping devices consist of the following: 14 indicates a pair of integral lugs on the wall of the head 6 at one side of the split and formed with openings through which extend bolts 15 having heads, preferably consisting of nuts 16 threaded on their outer ends, arranged to engage the outer sides of the lugs 14. The inner ends of the bolts 15 terminate in collars 17, the inner walls of which form bearings for eccentrics 18 fixed to a shaft 19, which is rotatably supported in hollow bosses 20 formed integrally on the wall of the head 6 on the other side the split 13. The shaft 19 is provided with tool engaging means for rotating it and the eccentrics, such rotation serving to draw the walls of the split 13 together to clamp the head 6 to the shaft. 40 The nuts 16 are preferably adjusted on the bolts 15 so that when the throw of the eccentrics 18 is in line with the axes of the bolts 15, the head 6 is clamped to the shaft 5 and the eccentrics bearing on "dead center" the shaft 19 is held against rotation and release of the head 6. The registering means 12 consists of the following: 21 indicates openings formed in the lower end of the head 6, each corresponding to the operative position of one of the drums 10. Each opening 21 is 50 arranged to receive a plunger 22 when brought into registry therewith, the plunger being slidably supported in an opening 23 formed in the off-set portion of the base 4. The plunger 22 is normally urged upwardly into the openings 21 by 55

10

55

a coil spring 24 interposed between it and a portion of the base 4, such base portion being provided with an up-standing pin 25 which projects into the lower end of the spring to maintain it 5 in position. The plunger 22 is provided with oppositely disposed, lateral pins 26, which are engaged by the bifurcations on one end of a bell-crank 27, the opposite end of which is pivoted to one arm of a foot pedal 28, the bell-crank 27 and 10 pedal 28 being suitably fulcrummed on the base 4 (see Figs. 2, 5 and 6). As will be understood from Fig. 5, application of pressure downwardly on the outer end of the pedal 28, will effect a withdrawal of the plunger 22 from the adjacent 15 opening 21, following which the head 6 may be rotated to bring the other drum 10 into operative position (provided the clamping means 11 have been operated to unclamping position). The pedal 28 is fixed to its fulcrum 29, one end 20 of which is extended to support a latch 30. The latch 30 is adjustably fixed to the fulcrum 29 by a set screw 30a (Fig. 4.) The latch 30 is adapted to be engaged and locked by a shoulder on one arm 31a of a pivoted detent 31a, the other arm 31b 25 of which serves as a foot pedal to release the detent arm 31 from the latch 30. The arm 31 is normally biased into latch locking position by a spring 30x. The lower side of the latch 30 adjacent its outer end is beveled or rounded (see 30 dotted lines in Fig. 5), so that when the pedal 28 is forced downwardly to withdraw the plunger 22, the latch 30 rides the detent arm 31 to permit the shoulder on the outer end of the latter to engage the upper side of the latch, the effect 35 of which is to lock the latch 30 against return movement under the influence of the spring 24 and hold the plunger 22 in retracted position. To release the latch 30, downward pressure is applied to the detent arm or pedal 31b to release 40 the latch 30, whereupon the spring 24 will move the plunger 22 upwardly.

The drums 10 are adapted to receive coils of material A and support them while the material of one coil is being un-coiled; that is, one drum 45 is loaded with a coil of material and then the head 6 is rotated to position the drum and coil thereon in operative relation to the operating mechanism 2, as shown at 10 (Figs. 1 and 2); while the material of that coil is uncoiling, a 50 separate coil of material is loaded on the other drum 10; then when the material on drum 10 has been uncoiled and delivered therefrom, the head 6 is rotated to position the drum 10' in operative relation to the mechanism 2 and while 55 the material of the coil thereon is uncoiling a separate coil of material is loaded on the drum 10. For this purpose, each drum comprises a shell 32 formed with spaced, longitudinally extending openings 33, in each of which a member 60 34 operates radially. With the members 34 in retracted or collapsed position, a coil A may be positioned on the shell; the members 34 are then operated or expanded radially simultaneously, the effect of which is to engage the inner convolution of the coil A and accordingly secure the coil to the drum. The inner end of the shell 32 is provided with an inturned flange integrally connected to a ring 35. The ring 35 is sweated onto a collar 36 which rotatably supports the inner end of the drum on the adjacent shaft 9. The collar 36 is held against the outer end of the adjacent boss 8 by a ring 36a fixed to the shaft 9 by a suitable set screw (see Fig. 2). The collar 36 is preferably integrally connected to a 65 disk 37, the marginal portion of which is pro-

vided with an annular wall forming a brake drum 38 for a brake band 39. One end of the band 39 is normally fixed, as later set forth, whereas its opposite end is connected to a rod 40, which is adapted to slide endwise in an opening formed on the outer end of a rod 41, the latter being supported by a projection 42 formed integrally with the adjacent boss 8. The outer end of the rod 40 is provided with a head 43 (preferably consisting of a nut threaded on the rod 10 and a lock nut 43a therefor), between which and the rod 41 is provided an expansion spring 44, coiled around the rod and adapted to normally exert tension through the rod 40 on the brake band 39 to effect a predetermined frictional engagement with the drum 38, whereby the rotation of the adjacent drum 10 is retarded during the uncoiling of the material therefrom. By adjusting the head 43, the braking effect of the band 39 on the drum 38 may be readily increased or decreased. The normally fixed end of the band 39 is releasably connected to the projection 42, whereby the band may be disengaged from the drum 38 when it is desired to permit the drum 10 to freely rotate on its shaft. 25 For this purpose, the end of the band 39 remote from the rod 40 terminates in a loop or eye 44', which receives a pin 45. The pin 45 is mounted eccentrically on a disk 46 fixed to a shaft 47, the latter being mounted in an opening 48 formed 30 in the projection 42. The disk 46 is provided with a handle 49, whereby it may be rotated, the operation of the handle 49 to the position shown in dotted lines in Fig. 3 serving to move the pin 45 about the axis of the disk and thus 35 effect a release of the brake band 39 from its drum 38.

The disk 37 is provided with a plurality of radially extending slots 50, one for each expandible element 34. The rear end of each element 40 34 is provided with an extension 51, which extends through the adjacent slot and is provided on the outer side of the disk 37 with wings 34a which co-operate with the inner end of the member 34 to slidably connect the latter to the disk 45 for guided movement radially outwardly and inwardly.

The outer end portion of the shell 32 is preferably provided with a conically shaped wall 32a to facilitate loading of the coils of material 50 thereon and an inwardly extending, annular wall 52, which is concentric to the drum axis and is adapted to slidably mount the outer end of a sleeve 53. The sleeve 53 is rotatably mounted on the shaft 9 to support the outer end of the drum 10 thereon. The outer end of the sleeve 53 is provided with an end wall 54 formed with an axial opening in which is fixedly mounted a nut 55. A screw 56, which is threaded through the nut 55, is connected to a shaft 57 rotatably mounted in an opening formed in a cap plate 58, the latter being suitably secured to the shell 32 at the outer end of the wall 52. The outer end of the shaft 57 is shaped to take a suitable tool or crank (not shown) whereby it may be rotated. 60 The shaft 57 is provided with collars 59, 59a, disposed on opposite sides of the cap plate 58, and serve to prevent endwise movement of the shaft 57 when rotated, whereby rotation of the shaft 57, through the screw 56 and nut 55, will effect 65 endwise movement of the sleeve 53. As the sleeve 53 is connected by pairs of links 60 to the expandible members 34, and the latter are guided for movement radially, as already set forth, movement of the sleeve 53 endwise in one 70 75

direction will move the members 34 outwardly and the endwise movement of the sleeve 53 in the opposite direction will retract or move the members 34 inwardly. In the arrangement of the links 60, as shown in Fig. 2, endwise movement of the sleeve 53 inwardly serves to expand the members 34.

The mechanism 2 shown herein for illustrative purposes for operating on the material A while it is feeding from an uncoiling drum 10 or 10' to a re-coiling drum 10x or 10x' of the mechanism 3, consists of a slitting mechanism which may be substantially similar to that shown in the application for Letters Patent Ser. No. 12,818, filed 15 March 25, 1935, by Carl M. Yoder, of Lakewood, Ohio, now Patent No. 2,160,999 of June 6, 1939, but it will be understood that any other type of mechanism for operating on the material may be employed; for example, devices for polishing 20 the surface of sheet metal, mechanism for leveling the material or punching elements for various kinds of sheet material. In the form of construction shown, the mechanism 2 is provided with four sets of slitting elements 61, 61', mounted 25 ed on upper and lower shafts 62 suitably mounted in standards and driven by a motor 63, whereby the material A is slit into three strips a; but it will be obvious that the number of slits and width of the strips may be varied at will. As shown, 30 the slitting elements 61' serve to trim the longitudinal edges of the material A, the resulting trimmed off edges being deflected downwardly by suitably mounted rolls 61a, whereas the slitting elements 61, serve to slit the intermediate 35 portion of the material. The strips a are fed or delivered to one of the drums 10x, 10x', of the mechanism 3 for re-coiling, as later set forth.

The mechanism 3 consists of a base 4 supporting a shaft 5, on which rotates a head 6', held in position by a cap 7'. The head 6' is provided with diametrically arranged hollow bosses 8' in which are fixedly mounted the inner ends of shafts 9'. These parts are substantially similar to like parts of the uncoiling mechanism 1. 45 Each shaft 9' rotatably supports a drum, one drum being designated 10x and the other drum 10x'. The head 6' is held in predetermined positions each corresponding to the operative position for one of the drum 10x, 10x', by clamping 50 means 11' and registering means 12', each said means being preferably similar in construction to that heretofore described, like parts of each of said means shown in Figs. 1, 6 and 7 being designated by the same reference characters, 55 respectively.

Each re-coiling drum 10x, 10x', comprises the following: 64 indicates a body or hub member rotatably fitting the adjacent shaft 9' and held thereon by a cap 65 suitably bolted to the outer 60 end of the shaft. 66 indicates a clutch element suitably fixed to the outer end of the hub member 64, axially thereof, and adapted to be engaged by and disengaged from a clutch element 66a, which is drivingly connected to a power mechanism, indicated as an entirety at 67, later referred to. The clutch element 66 is recessed on its inner side to enclose the cap 65 and also cut away at one side, as shown in Fig. 6, to permit access to the cap and the securing bolts therefor. 65 The rear end of the hub member 64 is suitably secured to a disk 68, the marginal portion of which forms a rim or flange for the inner end of the drum. Means are provided for preventing, at will, free rotation of the drum in either direction. Such means may consist of a brake such

as shown applied to the drums 10, 10', but by preference I employ for this purpose a pawl and ratchet which prevents rotation of the drum in the strip uncoiling direction. For this purpose, the outer face of the disk 68 is provided with an annular ratchet 69 adapted to be engaged by a pawl 70 to prevent rotation of the drum in the strip uncoiling direction, but permits rotation thereof in the re-coiling direction. The pawl 70 is mounted on the inner end of a rod 71 which is rotatably and slidably mounted in an opening 72 formed in a lug 72a on the adjacent boss 8', a coil spring 73 being interposed between the lug 72a and a collar or enlargement on the inner end portion of the rod 71 and normally tending to project the latter into engagement with the ratchet 69. One side of the rod 71 is provided with a wing 74 which fits into an off-set recess leading from the opening 72. The wing 74 when lying in the recess as shown in Fig. 10, prevents the rod 71 from rotating and insures a predetermined operative relation of the pawl 70 with respect to the ratchet 69; but by retracting the rod 71 against the tension of the spring 73 by means of a head 71a on its outer end and then 25 rotating the rod a short angular distance, the wing 74 may be engaged with the outer face of the lug 72a, whereby the pawl 70 is held clear of the ratchet 69 to permit rotation of the drum 10x in either direction. Such free rotation of 30 the drum may be desirable to facilitate tying and unloading or removing each coiled strip a from the drum. The shell of the drum 10x consists of a stationary arcuate section 75 formed integrally with the hub member 64, arcuate side 35 sections 76 along either side of the section 75 and pivoted thereto by related knuckles 77 (see Fig. 8) and an intermediate movable section 78 provided with pairs of depending rods 79 disposed upon opposite sides of and parallel to a radius of 40 the axis of the drum, said rods 79 being guided in openings 80 formed in the hub member 64, to permit the intermediate section 78 to move radially outwardly and inwardly. The opposite side edges of the section 78 are inclined, downwardly and outwardly (see Fig. 7), and disposed in sliding engagement with the outer edges of the side sections 76, so that when the section 78 is moved outwardly, by means later referred to, it simultaneously swings the sections 76 about the 45 axes of the knuckles 77, whereby the drum is expanded, and when the section 78 is moved inwardly the sections 76 are free to swing inwardly under the influence of a spring 80' (which is connected at its opposite ends to bolts 81 carried 50 by the sections 76), whereby the drum is collapsed. The sections 76 and 78 are so arranged that when the latter is moved outwardly to the limit of its movement, the sections 75, 76, and 78 are substantially concentric to the axis of the 55 drum, in which position the sections are arranged when recoil of the strips a thereon takes place. By collapsing the sections as above set forth the re-coiled material may be readily removed. The means for moving the drum section 78 outwardly consists of the following: the opposite ends of the hub member 64 below the section 78 are provided with upwardly and inwardly inclined surfaces 82 and in opposed relation to each surface 82 the section 78 is provided with a reversely 60 inclined surface 83. 84 indicates a wedge block arranged between each said two related surfaces 82, 83 and having sliding engagement therewith. The wedges 84 are formed with aligned threaded, 65 through openings, one right-hand threaded and 70 left-hand threaded, 75

the other left-hand threaded, adapted to receive correspondingly threaded portions adjacent the opposite ends of a shaft 85, the rotation of which in one direction serves to move the wedges 84 toward each other, the effect of which is to move the sections 78, 76, outwardly and rotation of the shaft 85 in the opposite direction serves to move the wedges away from each other, whereby the section 78 is free to move downwardly (which movement will take place normally by reason of the inward pressure of the re-coiled material) and permit inward movement of the side sections 76. As shown in Figs. 6 and 8, the outer end of the shaft 85 is shaped to take a suitable tool or crank (not shown), whereby it may be readily rotated in either direction.

The power means 67 is shown as comprising a motor 86, the shaft of which through a suitable reduction gearing 87, drives a shaft 88, disposed axially of each drum 10x when in its operative position, the shaft 88 in turn being provided with a sleeve 89, which slides on the shaft but is keyed thereto. The outer end of the sleeve 89 is provided with the clutch element 66a, which is arranged to engage the clutch element 66 when the sleeve is moved outwardly. The sleeve 89 is provided with a pair of straps in which are formed elongated openings at diametrically opposite sides of the sleeve, these openings being arranged to receive inwardly extending pins provided on the arms of a yoke 90, which is preferably pivoted at its lower end on the block 92 fixed to the flooring, the upper end of the yoke being provided with a handle 93, whereby it may be operated from one position to its other position.

Operation: the drums 10, 10', are collapsed and a coil of material is mounted on the drum 10, which is then expanded. The head 6 is rotated to dispose the drum 10 in operative position (Fig. 1), as indicated by the dotted line x. The material A is then positioned and fed through the slitting elements and the free ends of the strips a bent laterally (as shown at a') and inserted in a groove or recess 94 formed in each drum wall section 75 of each drum 10x, with spacing rings 95 between them, thereby connecting the strips a to the drum. The clutch element 66a is connected to the clutch element 66 and the motor 87 started. Fig. 1 shows a coil of material a portion of which has been uncoiled from the drum 10 and coiled on one of the drums 10x; also the positioning of a separate coil A on the drum 10' while the material of the coil on the drum 10 is uncoiling therefrom. When the material on drum 10 has been completely uncoiled, the head 6 is rotated to dispose the drum 10' in operative position, the free end of the material thereon connected to one of the drums 10x and while uncoiling takes place, a new coil of material is positioned on the drum 10. The drums 10x are operated in the reverse manner, since the material is re-coiled on each thereof and removed. Fig. 1 shows the drum 10x' loaded with the coiled strips a thereon, and ready to be

removed while re-coiling takes place on the drum 10x. Each coil of strip material, before removal, may be tied with one or more wire loops (indicated in dotted lines at a'') for which purpose each of the drum sections 76 is formed with a groove 96 to permit the wire a'' to be threaded around the coiled strip.

It will be understood that the drums for the uncoiling mechanism may be similar in construction to that of the drums for the re-coiling mechanism, or vice versa, but in the preferred arrangement the uncoiling drums are shaped on their outer ends to form a guide for the coil in positioning it thereon, whereas the re-coiling drums are arranged to provide for the application of power to their outer ends; but obviously the power means for rotating the re-coiling drums may be mounted on the head 6'; also, each head 6, 6', may be arranged to support four shafts each supporting a drum 10'', as shown in Fig. 11. In the broader aspects of my invention, the number of drums mounted on one rotatable head may be greater than the number of drums on the head, since it is not necessary for the heads to support the same number of drums.

To those skilled in the art of making apparatus of the class described, many alterations in construction and widely differing embodiments and applications of my invention will suggest themselves, without departing from the spirit and scope thereof. My disclosures and the description herein are purely illustrative and are not intended to be in any sense limiting.

What I claim is:

In apparatus of the class described, the combination of a head, a plurality of shafts rigidly mounted at their inner ends on said head in angular relation, an expandible drum rotatably mounted on each of said shafts and adapted to receive a coil of sheet material, said head being rotatably mounted whereby each of said drums may be swung to a predetermined position to permit the uncoiling of the material therefrom, a separate head spaced from said first mentioned head, a plurality of shafts rigidly mounted at their inner ends on said separate head in angular relation, an expandible drum rotatably mounted on each of said shafts and adapted to re-coil the material thereon, said separate head being rotatably mounted, whereby each of said last mentioned drums thereon may be swung to a predetermined position in alinement with the first mentioned, predetermined positioned drum, means for locking each head in each predetermined position, separate means between the separate head and the inner end of each re-coiling drum for preventing the latter from rotating in the uncoiling direction, means between the first mentioned head and the inner end of each un-coiling drum for retarding the rotation of the latter, and power means arranged to be detachably connected to the outer end of each re-coiling drum when it is in re-coiling position.

LEONARD A. YODER.
